UNITED STATES PATENT OFFICE

116,747

DESIGN FOR A FOOD MIXING APPARATUS

David A. Meeker, Troy, Ohio, and Egmont H. Arens, New York, N. Y., assignors to The Hobart Manufacturing Company, Troy, Ohio, a corporation of Ohio

Application November 6, 1937, Serial No. 72,656

Term of patent 14 years

To all whom it may concern:

Be it known that we, David A. Meeker and Egmont H. Arens, both citizens of the United States of America, residing at Troy, in the county of Miami and State of Ohio, and at New York, in the county and State of New York, respectively, have invented a new, original, and ornamental Design for a Food Mixing Apparatus, of which the following is a specification, reference being had to the accompanying drawing forming a part thereof, and in which

Fig. 1 is a view in perspective of a food mixing apparatus showing our new design; and

Figs. 2 and 3 are, respectively, a side elevational

and an end elevational view thereof on a smaller scale.

The design consists of a food mixing apparatus comprising a base portion, an upwardly sweeping pedestal, and a horizontally extending upper part overhanging the pedestal and the base, all of said parts being combined to result in the appearance substantially as shown.

We claim:

The ornamental design for a food mixing apparatus, substantially as shown and described.
